Alfred Schinstadt

ATTORNEY.

UNITED STATES PATENT OFFICE.

THOMAS DELIKAT, OF NEWARK, NEW JERSEY.

DESIGN FOR A COMBINED HATPIN AND POINT-PROTECTOR.

55,755.

Specification for Design.

Patented July 13, 1920.

Application filed September 25, 1919. Serial No. 326,400. Term of patent 3½ years.

To all whom it may concern:

Be it known that I, THOMAS DELIKAT, a citizen of Poland, and a resident of Newark, in the county of Essex and State of New Jersey, have invented a new, original, and ornamental Design for a Combined Hatpin and Point-Protector, of which the following is a specification, reference being had to the accompanying drawings, forming part thereof.

The figure is a plan view of a combined hatpin and point protector, showing my new design.

I claim—

The ornamental design for a combined hatpin and point protector, as shown.

THOMAS DELIKAT.
